[57] CLAIM

The ornamental design for an electrosurgical pencil, as shown and described.

DESCRIPTION

FIG. 1 is a perspective view of an electrosurgical pencil showing our new design;

FIG. 2 is a side elevational view thereof;

FIG. 3 is a top plan view thereof;

FIG. 4 is a bottom plan view thereof;

FIG. 5 is a left end elevational view;

FIG. 6 is a right end elevational view;

FIG. 7 is a perspective view of an electrosurgical pencil showing a second embodiment of our new design;

FIG. 8 is a side elevational view of the embodiment shown by FIG. 7;

FIG. 9 is a top plan view of the embodiment shown by FIG. 7;

FIG. 10 is a left end view of the embodiment shown by FIG. 7; and

FIG. 11 is a right end elevational view of the embodiment shown by FIG. 7.

The bottom plan view of the embodiment shown by FIGS. 7 through 11 is identical to FIG. 4.
